UNITED STATES PATENT OFFICE.

FREDERICK W. PARSONS, OF ELMIRA, NEW YORK, ASSIGNOR TO INGERSOLL-RAND COMPANY, OF JERSEY CITY, NEW JERSEY, A CORPORATION OF NEW JERSEY.

PLATE VALVE.

Application filed March 31, 1921. Serial No. 457,168.

To all whom it may concern:

Be it known that I, FREDERICK W. PARSONS, a citizen of the United States, and a resident of Elmira, county of Chemung, 5 State of New York, have invented a certain Plate Valve, of which the following is a specification accompanied by drawings.

This invention relates to plate valves for pumps, compressors, blowing engines and 10 the like, but more particularly to the type of plate valve disclosed in United States Patents Nos. 1,244,186 and 1,349,145 granted to J. C. Breinl, one of the distinguishing features of which among others, resides in 15 the fact that a valve guide formed separately from the valve plate and preferably having guide arms, is suitably attached to the valve plate at spaced points.

One method of attaching the valve guide 20 or guide arms to the valve plate is by welding, as for instance electric spot welding, but this method presents certain practical difficulties and disadvantages due in part to unsatisfactory means for controlling the 25 heat in order to avoid the weakening of the metal at the welds by too high temperature, the critical temperature being difficult of attainment with certainty.

On the other hand difficulty has been experienced in mechanically securing the valve 30 guide and valve plate together, as by means of rivets for instance, because rivets of various known types have been found to break or cause the guide arms or valve plate 35 to crack or break usually at or near the rivet holes under the severe strains, peculiar to this type of valve, to which the valve plate and valve guide are subjected in operation, particularly in high speed machines.

The objects of the present invention are 40 to secure satisfactory means which are at the same time simple and efficient for attaching the guide arms to a valve plate so that the valve guide, guide arms or valve plate 45 will not crack or break in practical operation, except perhaps under exceptional circumstances, against which contingency no safe guard can of course be absolutely relied upon. I have found however, that the 50 guide arms may be riveted to the valve plate

provided certain features of construction be followed in accordance with the underlying principles of my invention, discovered through actual experience, and such improved riveted construction obviates the disadvantages of welding, prevents breakage under all ordinary circumstances, and permits manufacture in quantity production with certainty, uniformity and precision.

Other features, hereinafter to appear, in 60 addition or complementary to the form of the rivets, enter into the construction and contribute to the solution of a mechanical problem which has proved to have great difficulties, owing apparently in large measure to the strains and stresses in plate valves 65 of the type referred to, which sometimes produce unexpected and undesirable results, not apparently deducible from known factors.

One of the preferred forms of my invention is shown in the accompanying drawings, in which I have chosen to illustrate a complete valve assembly of the plate valve type, in order to make all details of the invention clear. So much of the drawings 75 and specification as relate to the safety dowel for the spacing washer beneath the valve guide are covered by the copending application of Thomas J. Hart, Serial No. 456,597, filed March 29, 1921, but this feature is herein shown in order that the valve may be illustrated and described substantially as 80 actually manufactured.

In the drawings Figure 1 is a top plan view of a stop plate.

Figure 2 is a transverse sectional view of the stop plate on the line 2—2 of Figure 1 looking in the direction of the arrows.

Fig. 3 is a top plan view of the valve guide 90 and valve plate, with the springs omitted;

Figure 4 is a transverse sectional view of the valve guide and valve plate on line 4—4 of Figure 3 looking in the direction of the arrows with the springs in position over the 95 rivets;

Figure 5 is a detail perspective view of the valve guide;

Figure 6 is a detail perspective view of the valve plate;

Figure 7 is a detail perspective view of one of the rivets for riveting the guide arms to the valve plate;

Figure 8 is a perspective view of the spacing washer showing the safety-dowel;

Figure 9 is a top plan view of the valve seat;

Figure 10 is a transverse sectional view of the valve seat on the line 10—10 of Figure 9 looking in the direction of the arrows, and

Figure 11 is a transverse sectional elevation of the valve with the parts assembled taken on the line 10—10 of Figure 9.

Referring to the drawings and at first more particularly to the assembly shown in Figure 11, a discharge valve is illustrated, although the invention applies equally to an inlet valve, and the valve comprises a valve seat A having the ports B, a valve plate C, a valve guide D having a central body portion E and curved guide arms F attached to the valve plate C by means of the rivets G, a spacing washer H adapted to be arranged beneath the valve guide D and between the valve guide and the valve seat A, a stop plate or guard J having apertures K, and recesses L for the reception of springs O preferably adapted to be seated upon the rivets G, so that the springs do not bear directly upon the valve guide and any wear occurs upon the rivet heads rather than upon the metal of the guide. A suitable stud or bolt P having a nut Q is provided for holding the parts together.

A centering or aligning dowel R preferably secured to the valve seat A is provided for insuring the proper angular adjustment of the parts as assembled, and the washer H, the valve guide D, and the stop plate J are each provided with an aperture S through which the dowel R passes in assembling the parts. The washer H is also provided with a safety dowel T on one side adapted to enter the dowel hole U in the valve seat so that if the washer H should be placed over the valve guide, the safety dowel T would interfere with the proper assembly and indicate that the washer was in the wrong place.

In a valve of the type illustrated and described, it has been found desirable to make the valve guide D of thinner and more resilient material than the metal of the valve plate C and preferably construct the guide arms F narrower than the width of the valve plate. By such relative difference in the thickness and quality of the metal of the two parts and the narrower width of the guide arms, better results are obtained, especially in cooperation with the form of rivet construction shown.

In riveting the guide arms F and the valve plate C together the rivets are preferably placed at the ends of the guide arms and for this purpose rivet holes V are pro-

vided in the guide arms adapted to register with the rivet holes W in the valve plate. A substantial bearing surface should be provided between the valve guide or guide arms and the valve plate, which insures a more uniform bending action in the guide arms and body portion of the valve guide as the valve lifts and seats and tends to prevent breakage of the valve guide. In order to produce this substantial bearing surface between the guide arms and the valve plate, the heads X of the rivets are made materially larger in diameter than the body portions or shanks Y of the rivets. The rivet heads X are preferably made substantially equal to or greater in diameter than the width of the guide arms F as illustrated particularly in Figures 3 and 11 in which the rivet heads X are substantially equal in diameter to the width of the valve plate C and project slightly beyond the edges of the guide arm F. This construction as illustrated and described need not be followed in exact detail, since equivalent constructions may be devised for accomplishing the same objects.

The guide arms and valve plate are riveted together with the rivet heads on the guide arm side of the valve and the rivet shanks Y are preferably upset sufficiently at a to hold the rivets in position, without, however, appreciably expanding the said rivet shanks in the rivet holes in order to avoid initial strain on the metal of the guide arms and valve plate. The heads of the rivets are also preferably provided with reduced cap portions Z affording means for seating the coiled springs O over the rivet heads on said reduced cap portions. By this means the springs are centered and may be retained on the rivet heads.

I claim:

1. A sheet metal valve comprising a circular valve plate, and a valve guide provided with curved guide arms having substantially the same radius of curvature as the circular valve plate and riveted to the said plate, the heads of the rivets lying on the valve guide side of the valve plate being substantially equal to or greater in diameter than the width of the guide arms to afford a substantial bearing surface between the valve plate and the valve guide and to reinforce the said parts in the region at which the rivet hole is formed, the shanks of the rivets extending through the valve plate being materially smaller in diameter than the heads and sufficiently upset to hold the rivets in position.

2. A sheet metal valve comprising a valve plate in the form of a ring and a valve guide provided with a central portion and integral curved guide arms having substantially the same radius of curvature as the valve plate and being thinner and narrower

than the valve plate, the ends of said guide arms being riveted to the valve plate, the heads of the rivets lying on the valve guide side of the valve plate being substantially 5 equal to or greater in diameter than the width of the guide arms to afford a substantial bearing surface between the valve plate and the valve guide and to reinforce the said parts in the region at which the rivet hole 10 is formed, the shanks of the rivets extending through the valve plate being materially smaller in diameter than the heads and sufficiently upset to hold the rivets in position.

3. A sheet metal valve comprising a valve 15 plate in the form of a ring and a valve guide provided with a central portion and integral curved guide arms having substantially the same radius of curvature as the valve plate and being thinner and narrower 20 than the valve plate, the ends of said guide arms being riveted to the valve plate, the heads of the rivets lying on the valve guide side of the valve plate being substantially 25 equal to or greater in diameter than the width of the guide arms to afford a substantial bearing surface between the valve plate and the valve guide and to reinforce the said parts in the region at which the rivet hole is formed, the shanks of the rivets 30 which extend through the valve plate being materially smaller in diameter than the heads and sufficiently upset to hold the rivets in position without appreciably expanding

the said shanks to avoid strain on the metal of the guide arms and valve plate.

35

4. A valve comprising a seat, a circular valve plate, a guide provided with guide arms having substantially the same radius of curvature as the valve plate and being riveted to said valve plate, the heads of the rivets lying on the valve guide side of the valve plate being substantially equal to or greater in diameter than the width of the guide arms, coiled springs seated upon the heads of said rivets, a stop plate having 40 guide recesses for said springs, and means for holding the parts of the valve together.

45

5. A valve comprising a seat, a circular valve plate, a guide provided with guide arms having substantially the same radius of curvature as the circular valve plate and being riveted to said valve plate, the heads of the rivets lying on the valve guide side of the valve plate having flanges substantially 50 equal to or greater in diameter than the width of the guide arms and also having reduced cap portions, coiled springs seated on the reduced cap portions of the rivets for returning the valve plate to its seat after lifting, a stop plate having guide recesses 55 for said springs and means for holding the parts of the valve together.

55

In testimony whereof I have signed this specification.

FREDERICK W. PARSONS.
